[57] CLAIM

I claim the ornamental design to a shoelace securing system,
as illustrated.

DESCRIPTION

FIG. 1 is a perspective view;
FIG. 2 is a top plan view. A bottom plan view is a mirror image of the top plan view;
FIG. 3 is a front elevational view. A back elevational view is a mirror image of the front elevational view;
FIG. 4 is a right side view; and,
FIG. 5 is a left side view.
